[57] CLAIM

The ornamental design for a weather proof lantern, as shown and described.

DESCRIPTION

FIG. 1 is a perspective view of a weather proof lantern showing my new design;
FIG. 2 is an enlarged front elevational view thereof;
FIG. 3 is a rear elevational view thereof;
FIG. 4 is a top plan view thereof;
FIG. 5 is a bottom plan view thereof; and,
FIG. 6 is a right side elevational view thereof; the left side elevational view not shown as it is substantially the same as the right side elevational view.
